UNITED STATES PATENT OFFICE.

RAY W. DOVER, OF CAMBRIDGE, OHIO, ASSIGNOR OF ONE-HALF TO EARL BOYD, OF CAMBRIDGE, OHIO.

TOY.

Application filed May 19, 1926. Serial No. 110,210.

My present invention has reference to a walking toy, and aims to provide a grotesque figure, including a body, having movable legs, eyes and a lower jaw and which, when arranged on a incline is so constructed as to produce a rocking movement which causes a swinging of the legs and jaw to propel the figure and likewise causes the swinging of the eye portions to produce a grotesque and amusing effect.

To the attainment of the foregoing, the invention consists in the improvement as hereinafter described and definitely claimed.

In the drawings:

15 Figure 1 is a side elevation of the improvement, the dotted lines indicating the rocking movement of the figure which affords the propulsion thereof.

Figure 2 is a bottom plan view.

20 Figure 3 is a detail sectional view on the line 3—3 of Figure 1.

Figure 4 is a detail sectional view on the line 4—4 of Figure 3.

25 Figure 5 is a sectional view on the line 5—5 of Figure 1.

Figure 6 is a detail sectional view on the line 6—6 of Figure 5.

As disclosed by the drawings, the toy is shaped to produce a grotesque figure and is 30 painted or otherwise ornamented to enhance its fantastic appearance. The figure may be shaped to represent some prehistoric animal or reptile and in the showing of the drawings the figure has its body portion 2 formed 35 with a tail 3 and with a head 4. The lower jaw 5 of the figure is loosely hinged to the body thereof, as at 6, and the head portion of the figure has its sides provided with round openings 7. The top of the head is

40 formed with longitudinal slits or kerfs 8 that intersect the inner walls provided by the openings 7, and in these slots or kerfs 8 there are hung from a pin 9 the straight ends 10 of discs 11. The discs have their 45 outer faces painted to represent eyes and as the said discs are freely hung it will be apparent that the same will swing on the pivot 9 when the figure is in motion. The jaw 5 upon its lower face and adjacent to its outer

50 end, is formed with a lug 12. The belly portion of the body 2 from its jaw, is rounded outwardly, as at 13, the said rounded portion being formed with a transverse opening in which there is seated a strip 14 55 which has its outer face rounded and which

extends a suitable distance beyond the outer wall or belly portion 13. From thence the belly portion of the figure is cut inwardly and from thence inclined or rounded to the tail 3, the outer end of the said tail portion 60 being flat.

The strip 14 provides a fulcrum element for the figure and the body thereof, inward of the fulcrum element 14, is notched and is formed with a round opening 16. Adapted to pass through this opening 16 there is a pin 17 that is secured to the leg members 18 of the figure. Each of the leg members is pivoted, as at 19, to the sides of the body 2 65 of the figure. The leg members are comparatively wide, the outer or toe portions thereof are widened and have their outer ends rounded, as at 20.

It is to be noted that the head portion of 70 the figure is of a greater width than the tail portion thereof and when the figure is arranged on an inclined plane, as illustrated in Figure 1 of the drawings, and the tail portion is tapped, the figure will rock to the position illustrated by the full lines in Figure 1 of the drawings. This causes the opening of the movable jaw 5 and permits of

75 the rounded ends of the legs 18 contacting with the surface on which the figure is arranged. The weighted headed end of the figure will return the same to its initial position, which causes the leg members to be 80 swung to the dotted line position, the jaw 5 to be closed. The leg members by the weight thereof will return to ground contacting position so that the figure will be 85 propelled as long as the same is arranged upon the inclined plane. The swinging of the jaws and the legs and the movement of the eyes of the figure will produce an amusing effect upon the operator or the audience. The swinging of the legs, is, of course, limited by the contacting engagement of the pin 17 with the opposite walls provided by 90 the opening 16 and the simplicity and advantages of my grotesque toy will, it is thought, be apparent when the foregoing description is taken in connection with the accompanying drawings without further detailed description.

Having described the invention, I claim:

1. A toy as herein described, comprising a body having a head and a tail, the head portion of the figure being of a greater weight than the tail, weighted eyes pivot- 110

ally secured on the head of the body, a lower jaw pivotally secured on the body and having its outer end formed with a downwardly extending lug, said body having its belly portion rounded and provided with an outwardly projecting fulcrum, leg members pivotally secured to the sides of the body and having rounded ends which are disposed opposite the fulcrum and means limiting the swinging of the leg members in both directions.

2. A toy as herein described, comprising a body having a tail extension and a head, said head having openings entering from the sides thereof and having longitudinal kerfs at the terminal of the openings, disc members received in the kerfs and arranged opposite the openings and pivotally sup-

ported in said kerfs, a lower jaw for the head portion of the body hingedly connected to the body, the belly portion of the body being rounded, a transversely arranged outwardly extending fulcrum member in the belly portion of the body, said body, from the fulcrum member being cut inwardly and directed toward the tail and provided with a transverse rounded opening, leg members pivoted to the opposite sides of the body having their outer ends rounded and disposed opposite the fulcrum member and a pin connecting the leg members and passing through the said rounded opening in the body.

In testimony whereof I affix my signature.

RAY W. DOVER.
